(57) **CLAIM**

The ornamental design for an air mattress assembly, as shown and described.

DESCRIPTION

FIG. 1 is a front, left and top perspective view of an air mattress assembly showing my design.

FIG. 2 is a front, left and top perspective view of an air mattress base of the air mattress assembly in FIG. 1.

FIG. 3 is a rear, right and bottom perspective view of the air mattress base of FIG. 2.

FIG. 4 is a front elevation view of the air mattress base of FIG. 2.

FIG. 5 is a rear elevation view of the air mattress base of FIG. 2.

FIG. 6 is a left side elevation view of the air mattress base of FIG. 2.

FIG. 7 is a right side elevation view of the air mattress base of FIG. 2.

FIG. 8 is a top plan view of the air mattress base of FIG. 2.

FIG. 9 is a bottom plan view of the air mattress base of FIG. 2.

FIG. 10 is a front, left and top perspective view of a cushion of the air mattress assembly in FIG. 1.

FIG. 11 is a rear, right and bottom perspective view of the cushion of FIG. 10.

FIG. 12 is a front elevation view of the cushion of FIG. 10.

FIG. 13 is a rear elevation view of the cushion of FIG. 10.

FIG. 14 is a left side elevation view of the cushion of FIG. 10.

FIG. 15 is a right side elevation view of the cushion of FIG. 10.

FIG. 16 is a top plan view of the cushion of FIG. 10; and,

FIG. 17 is a bottom plan view of the cushion of FIG. 10.

The base and cushion of the air mattress assembly are shown separately in FIGS. 2–9 and FIGS. 10–17 to show aspects of the design that are not visible when combined.

(Continued)

The broken lines depict portions of the air mattress assembly that form no part of the claimed design.
